UNITED STATES PATENT OFFICE.

ELVAH O. BULMAN, OF GRAND RAPIDS, MICHIGAN.

LATCH.

1,324,953.

Specification of Letters Patent. Patented Dec. 16, 1919.

Application filed March 25, 1919. Serial No. 285,074.

To all whom it may concern:

Be it known that I, ELVAH O. BULMAN, a citizen of the United States of America, residing at Grand Rapids, in the county of Kent and State of Michigan, have invented certain new and useful Improvements in Latches; and I do hereby declare the following to be a full, clear, and exact description of the invention, such as will enable others skilled in the art to which it appertains to make and use the same.

This invention relates to latches and is particularly concerned with the production of latches for doors of simple construction and easy action, made entirely from sheet metal and with an operating handle pivotally mounted so as to fulcrum on the case through which it passes, whereby a particularly efficient and easy acting latch is produced. The invention includes various novel combinations and arrangements of parts and elements for producing these results as well as many other, as will hereinafter more fully appear, reference being had to the accompanying drawing in which various forms of the invention are shown, and in which,

Fig. 1 is a front elevation of a latch and coacting strike therefor, the same being mounted on a door and door jamb, respectively, which are shown fragmentarily.

Fig. 2 is a vertical section through the door and latch.

Fig. 3 is a horizontal section taken through the latch above the handle and looking down on the same.

Fig. 4 is a front elevation of the strike.

Fig. 5 is a side view thereof.

Fig. 6 is a partial vertical section and side view of a modified form of the latch, the case or housing being in section.

Fig. 7 is a view similar to Fig. 3 of this modification.

Fig. 8 is a side elevation with a part of the case broken away and in section, showing a still further modification.

Fig. 9 is a view similar to Figs. 3 and 7 of this last modification, and

Fig. 10 is an enlarged fragmentary section through the parts of the latch mechanism of the last modification illustrating the method of operation thereof.

Like reference characters refer to like parts in the different views of the drawing.

The latch is adapted to be attached at the free vertical edge of a door 1, and comprises a sheet metal case or housing 2 with upper

and lower ears 3 through which screws 4 may pass into the door for attachment. A handle, also of sheet metal, indicated at 5, passes through a front opening 6 in the housing. Inside of the housing the handle is formed with downwardly extending sides 7 in which slots 8 are cut, the same extending downwardly and forwardly toward the door at an angle to the vertical as shown in Fig. 2. These slots are located a short distance in front of the crown of the housing and a pin 9 disposed between and supported by the sides of the housing passes through the slots. In the form shown in Figs. 1 to 3 inclusive, the handle is extended in front of the pin for a distance and at its inner end has a strike engaging arm 10 formed which passes laterally through an opening 11 at the inner edge of one side of the housing, so as to pass across the meeting edges of the door and the door jamb. A spring 12 serves to elevate the inner end of the handle.

The strike 13 is attached to the door jamb 14 by screws or the like and is formed from a single piece of sheet metal with a flat top and inwardly extending sides and ends. A part of the metal of the top is struck outwardly and upwardly at an angle making a cam-like projection 15 above an opening 16 in the top of the strike so that the end of the arm 10, when brought against it in closing the door is forced downward against spring 12 until it passes into and through the opening 16 and behind a shoulder 17 made on one of the sides of the strike by cutting away the metal, as shown in Fig. 5.

The handle fulcrums on the upper edge of the opening 6 in the housing through which it passes. It is evident that if the outer depending end of the handle is grasped and an outward pull made thereon, the spring 12 may be compressed and the arm 10 lowered sufficient to disassociate with the shoulder 17 whereupon the door may be opened. It will be noted that with the pivotal movement of the handle, there is also a movement inward into the case caused by the engagement of pin 9 with the inclined sides of the slots 8, and as the handle returns to normal position there is a corresponding outward movement of the handle as a whole, this causing the arm 10 to have a tendency to move outward. When it engages behind the shoulder 17, accordingly, there is a drawing effect produced whereby the door is drawn tightly shut by spring pressure without the neces-

sity of inclining the shoulder 17 to the vertical; and on operation of the handle to release the latch, the inward movement of the arm immediately frees the strike from bearing engagement with the arm 10, there being little or no wear of the engaging parts, and furthermore, the pivotal movement of the handle about the upper edge of the opening 6 in the housing gives a particularly easy 10 action.

The handle may be extended through the door and provided with a thumb piece 18 at its end associated with which a handle 19 may be fixed to the opposite side of the door 15 for operation of the latch from either side, in those doors, such as screen doors or the like which need to have their latches operable from both sides.

In Figs. 6 and 7 a modification in construction is shown. The handle 5^a terminates with its slotted sides or ears 7^a, passing through the opening 6 in the crown of the housing, however, and having the pin 9 passing through the slots in said ears. A member 20 of sheet metal with depending sides 21 is pivotally mounted on the pin 9 and extends inward and is formed with a lateral arm 10^a similar to the arm 10 first described.

A lip 22 with its free end turned down to 30 bear against the upper side of member 20 extends from the inner end of the handle so that on operation of the handle about its fulcrum on the housing the arm 10^a may be disengaged from the strike which is the same 35 in construction as that described with reference to the first form of latch. The member 20 is normally elevated by the spring 12. With this construction a latching and unlatching of the door is accomplished practically the same as before except that on 40 pushing the door shut only the member 20 has to move and one grasping the handle 5^a as the door is closed does not feel any movement of the handle which is independent of 45 the latching member 20 and does not have to move therewith. It is also obvious that with this construction the extension terminating in a thumb piece 18 may be used if desired.

In Figs. 8, 9 and 10 a still further modification in structure is shown, the handle 5^b passing through the opening 6 in the crown of the housing as before and terminating in two sides or ears 7^b in which slots 8^b are cut, 55 the pin 9 passing therethrough. A latching member having an under side 23 and upturned vertical sides is pivoted at its outer end on the pin 9 and said under side at its outer end is turned upwardly as indicated 60 at 24 coming directly beneath a lip 25 which is an extension of the upper side of the handle at its inner end. Upward operation of the handle turning about the fulcrum provided at the upper edge of the opening 6 65 depresses lip 25 and causes an elevation of

the inner end of the latching member and its lateral arm 10^b, against the force of the spring 12^b which exerts a downward pressure on the latching member in this case. The strike must be modified so that the opening through the face thereof is above the cam 15^b and this cam inclines downwardly and outwardly instead of upwardly and outwardly as before. There is a lift of the arm 10^b to disengage from the strike instead of 75 a depression as in the first two modifications.

The simplicity of construction and ease of operation due to the constructions described render this latch one of great merit both from standpoints of utility and manufacturing.

I claim:

1. A latch comprising a housing having an opening through the outer side thereof, a handle passing through said opening, a pin 85 disposed horizontally between the sides of the housing, slots in the handle through which the pin passes whereby the handle fulcrums on the adjacent upper edge of the opening through the housing, and latching 90 means adapted to engage with a strike operated by the handle, substantially as described.

2. A latch comprising a support having spaced apart sides and a front portion having an opening therethrough, a handle passing through said opening, means on the support with which the handle has sliding engagement whereby said handle fulcrums on the upper edge of the opening in said front 100 portion of the support, and latching means for yieldingly forcing the handle between its ends against the upper edge of said opening, means operated by the handle, said latching means being adapted to engage with a 105 strike and be disengaged from the strike by operation of the handle.

3. A latch comprising a housing having an opening through the outer side thereof, a handle passed through said opening, a pin 110 located between the sides of the housing in horizontal position, said handle having slots therein through which the pin passes whereby the handle may be turned upward about the upper edge of the opening in the housing 115 as a fulcrum pivot, and latching means including a laterally extending arm passing through a side of the housing operated by the handle, substantially as described.

4. A latch comprising a support having 120 spaced apart sides and a front portion having an opening therethrough, a handle passing through said opening, spring means forcing the handle at its upper side against the upper edge of the opening, means carried 125 by the support with which the handle has sliding engagement, said means being located inside of the front portion of said support, and a laterally extending latching arm extending through a side of the support and 130

adapted to engage with a strike, said arm being operatively connected with the handle whereby upward pivotal movement of the handle about said upper edge of the opening 5 serves to disconnect said arm from the strike, substantially as described.

5. In a device of the character described, a strike formed from a single piece of sheet metal having an outer face and inwardly 10 extending sides, with a section of metal from the face struck out and turned at an angle to the vertical, an opening for the passage of a latching arm being provided by striking out said section, and with a shoulder formed in one side of the strike by cutting away the metal from said side back of 15 said outturned section, substantially as described.

6. A latch comprising a support having 20 spaced apart sides and a front portion between the sides having an opening therethrough, a pin disposed horizontally between the sides of the support, a latching member pivotally mounted adjacent one end 25 on said pin and including a laterally extending arm at its opposite end passing through a side of the support, means for turning said latching member about its pivot, and a handle passing through said 30 opening in the front portion of the support and engaging with the latching member whereby on turning the handle about the upper edge of said opening as a pivot, the arm may be moved in a direction opposite to 35 that imparted by the latch member turning means, substantially as described.

7. A latch comprising a support having spaced apart sides and a front portion between the sides provided with an opening 40 therethrough, a pin disposed horizontally between the sides of the support, a handle passing through said opening and formed with slots at its inner end through which the pin passes, a latching member pivotally 45 mounted at one end on the pin and extending inwardly away from the inner end of the handle, said latching member having a laterally extending arm at its opposite free end, spring means tending to turn the latching 50 member in one direction about its pivot, and interengaging means on the adjacent ends of the handle and latching member for turning the latching member against the force of the spring on operation of the 55 handle about the upper edge of the open-

ing in the support as a pivot, substantially as described.

8. A latch comprising a housing having an opening in the crown thereof, a pin disposed between the sides of the housing, a latching member pivotally mounted on the pin at one end and provided with a part at 60 said end extending above the center of the pin and located between the pin and the crown of the housing, an arm extending laterally through a side of the housing at 65 the opposite end of the latching member, a handle passing through the opening in the housing and formed with two spaced apart ears having slots therein through which the pin passes, said handle at its inner end passing over said upwardly extending part of the latch member, and a spring normally tending to turn the latching member in a 70 downward direction about its pivot. 75

9. A latch comprising a support having spaced apart sides and a front portion between the sides having an opening therethrough, a handle passing through said opening and formed at its inner end with 80 spaced apart ears, each having a substantially vertical slot therein, a pin carried by and between the sides of the support and passing through the slots, a latching member pivotally mounted at one end on the pin, 85 said latching member having a laterally extending arm at its opposite end, spring means tending to force the free end of the latching member in a downward direction, and operative engaging means between the 90 handle and latching member for elevating the free end of the latching member on turning the handle about the upper edge of the opening in the front portion of the support, 95 substantially as described.

10. A latch comprising a housing having a front opening therein, a handle passing through said opening, and adapted to turn about the upper edge of the opening as a fulcrum, means connecting the handle to 100 the housing at a point within the housing and permitting the handle within the housing to move up and down a limited distance with respect to the housing, and latching means actuated by the handle as it is turned in an upward direction about the upper edge of the opening in the housing, substantially as described.

In testimony whereof I affix my signature.
ELVAH O. BULMAN.
